UNITED STATES PATENT OFFICE.

LEWIS WM. ENDER, OF FOUNTAIN CITY, WISCONSIN.

ENVELOPE OPENER.

Application filed October 24, 1925. Serial No. 64,640.

This invention relates to improvements in envelopes and to means for opening the same, an object being to provide an envelope of novel construction having means whereby it may be opened without danger of mutilating its contents.

With the above and other objects in view, the invention further includes the following novel features and details of construction, to be hereinafter more fully described, illustrated in the accompanying drawings and pointed out in the appended claims.

In the drawings:

Figure 1 is a view of the blank of which the envelope is formed.

Figure 2 is a view showing the envelope partly folded.

Figure 3 is an enlarged fragmentary sectional view on the line 3—3 of Figure 2.

Figure 4 is a view showing the envelope just before the bottom flap is folded.

Figure 5 is a view of the completed envelope partly broken away.

Figure 6 is an enlarged fragmentary sectional view on the line 6—6 of Figure 5.

Figure 7 is a fragmentary view of a portion of the envelope illustrating the manner in which it is opened.

Referring to the drawings in detail where-
30 in like characters of reference denote cor-
responding parts, the reference character 10
indicates the body of the envelope which has
extending from one end what will be here-
inafter referred to as a long end flap, indi-
cated at 11. Extending from the opposite
35 end of the body is a relatively short flap 12,
so that the end flaps are of unequal length,
the construction of the envelope differing in
this respect from ordinary envelopes. Ex-
40 tending from the lower edge of the body is
a bottom flap 13, while extending from the
opposite edge is a closure flap 14.

Extending along the outer edge of the
45 flap 11 is an attaching flap 15 and this flap
is designed to be glued to the edge of the
body by means of the adhesive indicated at
16.

A flexible wire or cord 17 is looped over
50 the end flap 11 and may be arranged in the
form of an endless loop, or may be knotted
or otherwise connected as indicated at 18

with the ends twisted as shown at 19. The flap 12 is then folded over and glued to the body 10 along the edges indicated at 20 and 21, the last mentioned edge being glued upon 55 the cord so that the latter is securely held in place. The end 19 of the cord is prefer-
ably looped as shown in Figure 4 of the
drawings and the bottom flap 13 is glued
to the flaps 11 and 12 along the edges 22 60
so that the cord is held in position with its
extremity 23 projecting to form a gripping
portion. The closure flap 14 may then be
closed in the usual manner.

By pulling outward upon the extremity of 65
the cord, the end of the envelope may be
torn open as shown in Figure 7 of the draw-
ings without danger of mutilating its con-
tents.

The opening device or cord may be located 70
at either end of the envelope, but preferably
at the end to which the stamp is affixed, the
cord being practically entirely concealed and
out of the way.

The invention is susceptible of various 75
changes in its form, proportions and minor
details of construction and the right is here-
in reserved to make such changes as proper-
ly fall within the scope of the appended
claims.

Having described the invention what is
claimed is:

1. An envelope comprising a body, an end
flap of substantially the same size as the
body and folded over upon the rear face of 85
the latter, an attaching flap extending along
the outer edge of the end flap and folded
inward and secured to the adjacent end of
the body, a relatively small end flap extend-
ing from the end of the body opposite the
first mentioned flap and folded upon the 90
latter, a flexible member looped over the first
mentioned flap and extending downward be-
tween the flaps below the envelope, said rela-
tively small flap being sealed along its top
and inner edge, a bottom flap sealed upon 95
the end flaps and enclosing the ends of the
flexible member with the extremities of the
latter extending outward to provide a grip-
ping portion and a closure flap extending 100
from one edge of the body.

2. An envelope comprising a body, an end

2
flap foldable on said body and reaching to the opposite end of said body when folded thereon, a second end flap foldable over the free end of the first named flap, glue on both sides of the crease line made by folding the second flap securing the body and second named flap to the first named flap on oppo-

site sides thereof, a flexible member looped around the free end of the first named flap and cured thereto by the second named end flap, the body of the envelope and glue.

In testimony whereof I affix my signature.

LEWIS WM. ENDER.
